CONNECTOR HOUSING CONTAINING A WIRE TERMINAL WITH A MOLDED PORTION

BACKGROUND

Field of the Invention

The invention relates to a connector and a wire with terminal.

Description of the Related Art

Japanese Unexamined Patent Publication No. 2012-003856 discloses a connection that achieves anti-corrosion by crimping a barrel of a terminal fitting made of copper to a front end part of an aluminum core of a coated wire and then surrounding a crimped part of the core and the barrel in a liquid-tight manner by a molded synthetic resin. The barrel a base plate and two crimping pieces extend from both widthwise sides of the base plate. A front end part of the base plate is connected to a rear end part of a base of a terminal body.

The molded synthetic resin covers the barrel over the entire periphery. Thus, there is a height difference between the base of the terminal body and the lower surface of the molded synthetic resin and the posture of the terminal fitting may become unstable when the terminal fitting is inserted into a terminal accommodation chamber.

The invention was completed on the basis of the above situation and aims to stably accommodate a terminal fitting, in which a barrel is surrounded by a molded resin in a terminal accommodation chamber.

SUMMARY

A first aspect of the invention is directed to a connector with a coated wire including a core and an insulation coating surrounding the core. The core being exposed in a front end part. A terminal fitting includes a terminal body and a barrel formed in a rear end part of the terminal fitting. The barrel is crimped to surround the front end part of the coated wire. The barrel has a base plate connected to a bottom portion of the terminal body portion. The barrel has two crimping pieces extending from widthwise sides of the base plate. A molded portion surrounds the barrel over an entire periphery and covers the front end part of the coated wire in a liquid-tight manner. The connector further has a housing formed with a terminal accommodation chamber for accommodating the entire terminal fitting. The base plate is raised with respect to the bottom portion.

In the first aspect of the invention, the barrel may be crimped to surround an exposed area of the core without contacting the insulation coating. The molded portion may cover the entire exposed area of the core including a crimped part to the barrel and a front end part of the insulation coating in a liquid-tight manner. The entire terminal fitting and only an area of the molded portion before a front end of the insulation coating may be accommodated in the terminal accommodation chamber.

A second aspect of the invention is directed to an assembly of a coated wire with terminal fitting. The coated wire includes a core and an insulation coating surrounding the core. The core is exposed in a front end part. The terminal fitting includes a terminal body and a barrel formed in a rear end part of the terminal fitting. The barrel is crimped to surround the front end part of the coated wire. The barrel

2

includes a base plate connected to a bottom portion of the terminal body. The barrel has two crimping pieces extending from both widthwise side edges of the base plate. A molded portion surrounds the barrel over an entire periphery so that the molded portion covers the front end part of the coated wire in a liquid-tight manner. The entire terminal fitting is accommodated in a terminal accommodation chamber formed in a housing. The base plate is raised with respect to the bottom portion.

10 In the second aspect of the invention, the barrel may be crimped to surround an exposed area of the core without contacting the insulation coating. The molded portion may cover the entire exposed area of the core including a crimped part to the barrel and a front end part of the insulation coating in a liquid-tight manner. The entire terminal fitting and only an area of the molded portion before a front end of the insulation coating may be accommodated in the terminal accommodation chamber.

According to the first and second aspects of the invention, 20 a height difference between the lower surface of the bottom portion of the terminal body and the lower surface of the area of the molded portion surrounding the barrel can be reduced or eliminated. Thus, even if an inner wall of the terminal accommodation chamber has a flat shape, the terminal fitting can be accommodated in a stable posture in the terminal accommodation chamber.

According to the above-described configurations, since an insulation barrel to be crimped to the insulation coating is not formed in the rear end part of the terminal fitting, an area 30 of the molded portion surrounding the terminal fitting can be accommodated in the terminal accommodation chamber even without enlarging the volume of the terminal accommodation chamber.

35 BRIEF DESCRIPTION OF THE DRAWINGS

FIG. 1 is a perspective view of a connector of an embodiment.

FIG. 2 is a front view of the connector.

FIG. 3 is a section along X-X of FIG. 2.

FIG. 4 is a perspective view of a wire with terminal.

FIG. 5 is a side view of the wire with terminal.

FIG. 6 is a section of the wire with terminal.

FIG. 7 is a perspective view showing a state before a mold portion is formed in the wire with terminal.

FIG. 8 is a section showing the state before the mold portion is formed in the wire with terminal.

FIG. 9 is a plan view showing the state before the mold portion is formed in the wire with terminal.

50 DETAILED DESCRIPTION

Hereinafter, a specific embodiment of the invention is described with reference to FIGS. 1 to 9. Note that, in the 55 following description, a right side in FIGS. 3, 5 and 6 is defined as a front side concerning a front-rear direction. Upper and lower sides shown in FIGS. 2, 3, 5 and 6 are directly defined as upper and lower sides concerning a vertical direction. A connector A of this embodiment includes wires with terminals 10 and a housing 35.

The wire with terminal 10 is an integral assembly of a coated wire 11, a terminal fitting 15 and a molded portion 30 and constitutes a conductive path long and narrow in the front-rear direction. The coated wire 11 is composed of a core 12 made of aluminum or aluminum alloy and a substantially cylindrical insulation coating 13 surrounding the core 12. The insulation coating 13 is stripped by a prede-

terminated length on a front end part of the coated wire 11 to expose the core 12. The terminal fitting 15 to be described next is crimped and connected to a front end part of an exposed area 14 (see FIGS. 6 and 8) of this core 12.

The terminal fitting 15 is formed by applying bending and the like to a plate material made of copper or copper alloy stamped into a predetermined shape and shaped to be long and narrow in the front-rear direction. As shown in FIGS. 7 and 8, the terminal fitting 15 is composed of a terminal body 16 constituting a front end area of the terminal fitting 15 and a barrel 23 constituting a rear end area.

The terminal body 16 is composed of a box-shaped connecting portion 17 having a rectangular tube shape and a coupling 18 connected to the rear end of the box-shaped connecting portion 17. A tab of a mating male terminal (not shown) is inserted into the box-shaped connecting portion 17 from the front of the terminal fitting 15 to be connected. The coupling 18 is formed such that two side walls 20 rise from left and right sides of a bottom wall 19. The bottom wall 19 of the coupling 18 is continuous and flush with a lower wall 21 of the box-shaped connecting portion 17, and the bottom wall 19 and the lower wall 21 constitute a bottom portion 22 of the terminal body 16.

The barrel 23 is composed of a base plate 24 long and narrow in the front-rear direction and two crimping pieces 27 extending in a circumferential direction (direction intersecting a length direction of the terminal fitting 15) from both sides of the base plate 24 in a width direction (lateral direction). As shown in FIGS. 6 and 8, the base plate 24 is bent so that a front end part thereof is lowered via a step. In this way, a lower plate 25 is formed in the front end part of the base plate 24 and an area of the base plate 24 behind the lower plate portion 25 serves as a raised plate 26. A length of the raised plate 26 in the front-rear direction is set longer than a dimension of the lower plate 25 in the front-rear direction. The lower plate 25 is continuous and flush with a rear end part of the bottom portion 22 at the same height, and the raised plate portion 26 is raised with respect to the bottom portion 22.

The barrel 23 is crimped to the front end part of the coated wire 11 (core 12) by an automatic machine (not shown) called an applicator. In a crimping process, the two crimping pieces 27 are bent and deformed to surround the front end part of the core 12 placed on the rear end part of the base plate (raised plate 26). In this way, as shown in FIG. 8, a crimping space 28 surrounded by the base plate 24 and the two crimping pieces 27 is formed inside the barrel 23. The front end part of the core 12 accommodated in this crimping space 28 and the terminal fitting 15 are conductively fixed. In a crimped state, the front end part of the coated wire 11 and the terminal fitting 15 are connected substantially straight.

The core 12 is accommodated only in a rear end part of the crimping space 28 of the barrel 23, and a part of the molded portion 30 to be described later is filled in an area of the crimping space 28 before the core 12. Since the crimping space 28 of the barrel 23 is narrow, a means for making molten resin (not shown) easily flow into the crimping space 28 in a molding process of the mold portion 30 is necessary. As shown in FIG. 8, a communicating portion 29 is formed in an area of the barrel 23 before the front end of the core 12 by widening an interval between extending end parts 27E of the crimping pieces 27. The crimping space 28 and the outer peripheral surface of the barrel 23 are allowed to communicate by the communicating portion 29. The communicating portion 29 is open in a widthwise central part of the upper surface of the barrel 23. Further, a width of an

opening area of the communicating portion 29 in a plan view is substantially constant from a front end to a rear end.

The molded portion 30 is molded after the terminal fitting 15 is crimped to the core 12. The molded portion 30 is molded by accommodating the entire barrel 23, a rear end part of the coupling 18 and the front end part of the insulation coating 13 in the coated wire 11 into a known mold (not shown), injecting molten resin (not shown) into the mold and solidifying (curing) the injected molten resin. 10 In the molding process, part of the molten resin flows into the crimping space 28 of the barrel 23 via the communicating portion 29.

As shown in FIG. 6, the molded portion 30 after molding surrounds the entire barrel 23, the entire exposed area 14 of the core 12 including the crimped part to the barrel 23 and a front end part of an area of the coated wire 11 where the insulation coating 13 remains over the entire periphery in a liquid-tight manner. Further, a part of the front end part of the molded portion 30 is accommodated inside the coupling 18 before the barrel 23. The lower surface (outer surface) of a bottom area of the molded portion 30 covering the raised plate 26 of the barrel 23 is substantially at the same height as the lower surface (outer surface) of the bottom portion 22 of the terminal body 16, specifically slightly higher than the lower surface of the bottom portion 22.

As shown in FIG. 3, the wire with terminal 10 obtained by integrating the front end part of the coated wire 11, the terminal fitting 15 and the molded portion 30 is inserted into a terminal accommodation chamber 36 from behind the housing 35. In an inserted state, the entire terminal fitting 15 and most of the exposed area 14 of the core 12 excluding the rear end part are accommodated in the terminal accommodation chamber 36. Thus, an area of the coated wire 11 where the core 12 is surrounded by the insulation coating 13 is disposed entirely outside the terminal accommodation chamber 36 (housing 35).

An area of the molded portion 30 accommodated in the terminal accommodation chamber 36 and surrounding the entire terminal fitting 15 and the exposed area of the core 12 in a liquid-tight manner serves as an accommodating portion 31. An area of the molded portion 30 surrounding the rear end part of the exposed area 14 of the core 12 and the front end part of the insulation coating 13 in a liquid-tight manner behind and outside the terminal accommodation chamber 36 (housing 35) serves as a projecting portion 32. The projecting portion 32 of the molded portion 30 has a function of suppressing the influence of bending on the terminal fitting 15 when an area of the coated wire 11 behind the molded portion 30 is bent vertically.

Specifically, the projecting portion 32 of the mold portion 30 is formed with upper and lower reinforcing portions 34 as a reinforcing means 33 for enhancing the vertical bending rigidity of the molded portion 30. The reinforcing portions 34 make a thickness of the insulation coating 13 on an upper surface side and a thickness of the insulation coating 13 on a lower surface side larger than a thickness of the accommodating portion 31 substantially over the entire length of a projecting area. That is, the height of the molded portion 30 is larger in the reinforcing portions 34 (projecting portion 32) than in the accommodating portion 31. Note that a width of the reinforcing portions 34 (projecting portion 32) is equal to that of the accommodating portion 31.

As described above, the connector A of this embodiment includes the housing 35 formed with a plurality of terminal accommodation chambers 36 and a plurality of the wires with terminals 10 to be inserted individually into the respective terminal accommodation chambers 36. The wire with

terminal 10 includes the coated wire 11, the terminal fitting 15 and the mold portion 30. The coated wire 11 includes the core 12 and the insulation coating 13 surrounding the core 12, and the core 12 is exposed in the front end part of the coated wire 11. The barrel 23 crimped to surround the exposed area 14 of the core 12 without contacting the insulation coating 13 is formed in the rear part of the terminal fitting 15. Specifically, the barrel 23 is crimped to the front end part of the coated wire 11.

The molded portion 30 covers the front end part of the coated wire 11 (i.e. the entire exposed area 14 of the core 12 including the crimped part to the barrel 23 and the front end part of the insulation coating 13) in a liquid-tight manner. The core 12 is made of aluminum or aluminum alloy, whereas the terminal fitting 15 is made of copper or copper alloy. Thus, a contact part of the core 12 and the terminal fitting 15 (barrel 23) is surrounded in a liquid-tight manner by the molded portion 30 made of synthetic resin as an anti-corrosion means in the contact part of the core 12 and the terminal fitting 15 (barrel 23).

An outer diameter of the insulation coating 13 is larger than that of the core 12. Thus, an outer diameter of the area of the molded portion 30 surrounding the insulation coating 13 (projecting portion 32) is larger than that of the area of the molded portion 30 surrounding the core 12 (accommodating portion 31). In view of this point, an insulation barrel to be crimped to surround the insulation coating 13 is not formed in the rear end part of the terminal fitting 15 constituting the wire with terminal 10 of this embodiment. The entire terminal fitting 15 and the front end part of the molded portion 30 (i.e. only the area of the mold portion 30 before the front end of the insulation coating 13) are accommodated in the terminal accommodation chamber 36. However, the insulation coating 13 is not accommodated in the terminal accommodation chamber 36. This enables the entire area of the mold portion 30 surrounding the terminal fitting 15 to be accommodated in the terminal accommodation chamber 36 without enlarging the volume (height and width) of the terminal accommodation chamber 36.

The insulation barrel not formed in the terminal fitting 15 of this embodiment has a bending suppressing function of suppressing the influence of bending of the coated wire 11 outside the housing 35 on the crimped part of the terminal fitting 15 and the core 12. Thus, the molded portion 30 of this embodiment is required to have not only a waterproof function, but also the bending suppressing function instead of the insulation barrel. Accordingly, the wire with terminal 10 of this embodiment is provided with the reinforcing portions 34 as the reinforcing means 33 for enhancing the rigidity of the projecting portion 32 of the molded portion 30 projecting out from the housing 35.

The reinforcing portions 34 make the vertical thickness of the projecting portion 32 of the molded portion 30 projecting out from the housing 35 larger than that of the accommodating portion 31 of the molded portion 30 accommodated in the terminal accommodation chamber 36. According to this configuration, the vertical bending rigidity of the projecting portion 32 can be enhanced even without complicating the shape of the molded portion 30. Since the bending rigidity of the projecting portion 32 of the mold portion 30 is enhanced in this way, the projecting portion 32 is difficult to deform. In this way, the bending of the coated wire 11 does not affect the barrel 23 even if the coated wire 11 is bent behind the molded portion 30.

Further, the barrel 23 of the terminal fitting 15 includes the base plate 24 and the two crimping pieces 27. The base plate 24 is connected to the bottom portion 22 of the terminal

body 16 and the two crimping pieces 27 extend from the widthwise sides of the base plate 24. The barrel 23 is crimped and connected to surround the outer periphery of the core 12 placed on the base plate 24 by the two crimping pieces 27. This barrel 23 is surrounded over the entire periphery by the molded portion 30, but most of the terminal body 16 of the terminal fitting 15 before the barrel 23 is not covered by the molded portion 30. The entire terminal fitting 15 including the barrel 23 is accommodated in the terminal accommodation chamber 36 of the housing 35.

As described above, the molded portion 30 covers the base plate 24 of the barrel 23, but does not cover the bottom portion 22 of the terminal body 16. Thus, a step may be formed between the outer surface of the bottom portion 22 and the outer surface of the area of the molded portion 30 covering the barrel 23. If such a step is formed, a clearance is formed between the outer surface of the base plate 22 and the inner wall surface of the terminal accommodation chamber 36 when the terminal fitting 15 is accommodated into the terminal accommodation chamber 36. Thus the posture of the terminal fitting 15 in the terminal accommodation chamber 36 may become unstable.

Accordingly, the base plate 24 of the barrel 23 is raised with respect to the bottom portion 22 of the terminal body 16. According to this configuration, a height difference between the lower surface of the exposed bottom portion 22 of the terminal body 16 and the lower surface of the area of the molded portion 30 surrounding the barrel 23 can be reduced or eliminated. Thus, even if an inner wall of the terminal accommodation chamber 36 has a flat shape, the terminal fitting 15 can be accommodated in a stable posture in the terminal accommodation chamber 36.

Further, the barrel 23 formed in the rear end part of the terminal fitting 15 includes the two crimping pieces 27 extending from the both widthwise sides of the base plate 24, and is crimped to surround the exposed area 14 of the core 12 with the extending end parts 27E of the crimping pieces 27 held close to each other. The entire exposed area 14 of the core 12 including the crimped part to the barrel 23 is covered by the mold portion 30 in a liquid-tight manner.

In the wire with terminal 10 of this embodiment, the front end of the exposed area 14 of the core 12 is disposed behind the front end of the crimping pieces 27. Thus, in the molding process of the molded portion 30, the reliability of an anti-corrosion function needs to be enhanced by causing the molten resin to flow into the crimping space 28 of the barrel 23 without leaving any clearance and covering the front end surface of the core 12 by the molded portion 30. However, since the opening on the front end of the crimping space 28 of the barrel 23 is narrow, there is a problem that the molten resin is difficult to flow into the crimping space 28.

Accordingly, in this embodiment, the barrel 23 is formed with the communicating portion 29 for causing the crimping space 28 of the barrel 23 to be open in the outer peripheral surface of the barrel 23 before the front end of the core 12. By forming such a communicating portion 29, the molten resin more easily flows into the crimping space 28 of the barrel 23 by passing through the communicating portion 29 when the molded portion 30 is molded. Further, since the communicating portion 29 is formed between the extending end parts 27E of the crimping pieces 27, the base plate 24 needs not be cut and the strength of the base plate 24 is not reduced.

The invention is not limited to the above described and illustrated embodiment. For example, the following embodiments also are included in the scope of the invention.

Although the core of the coated wire is made of aluminum or aluminum alloy in the above embodiment, the material of the core is not limited to aluminum or aluminum alloy and may be another metal such as copper or copper alloy.

Although the terminal fitting is made of copper or copper alloy in the above embodiment, the material of the terminal fitting is not limited to copper or copper alloy and may be another metal such as aluminum or aluminum alloy.

Although the terminal fitting is not formed with the insulation barrel to be crimped to the insulation coating in the above embodiment, the present invention can be applied also when the terminal fitting is formed with the insulation barrel.

Although the insulation coating of the coated wire is not accommodated in the terminal accommodation chamber in the above embodiment, the front end part of the insulation coating may be accommodated in the terminal accommodation chamber.

LIST OF REFERENCE SIGNS

A . . . connector

The invention claimed is:

1. A connector, comprising:

a coated wire including a core and an insulation coating surrounding the core, the core being exposed in a front end part;

a terminal fitting including a terminal body with a bottom portion, and a barrel extending rearward from the terminal body, the barrel having a base plate connected to the bottom portion of the terminal body and raised with respect to the bottom portion, first and second crimping pieces projecting from opposite sides of the base plate, each of the first and second crimping pieces having ends spaced from the base plate, the first and second crimping pieces crimped to surround the front end part of the coated wire, and portions of the ends of the first and second crimping pieces at a front end of the barrel spaced from each other to define a communicating portion;

a molded portion surrounding the barrel over an entire periphery and entering the barrel through the communicating portion, the molded portion covering the front end part of the coated wire in a liquid-tight manner; and a housing formed with a terminal accommodation chamber for accommodating the entire terminal fitting.

2. The connector of claim 1, wherein:

the barrel is crimped to surround an exposed area of the core without contacting the insulation coating;

the molded portion covers the entire exposed area of the core including a part crimped by the barrel and a front end part of the insulation coating in a liquid-tight manner; and

the entire terminal fitting and only an area of the molded portion before a front end of the insulation coating are accommodated in the terminal accommodation chamber.

3. A wire with terminal, comprising:

a coated wire including a core and an insulation coating surrounding the core, the core being exposed in a front end part of the coated wire;

a terminal fitting including a terminal body with a bottom portion, and a barrel extending rearward from the terminal body, the barrel having a base plate connected to the bottom portion of the terminal body and raised with respect to the bottom portion, first and second crimping pieces projecting from opposite sides of the base plate, each of the first and second crimping pieces having ends spaced from the base plate, the first and second crimping pieces crimped to surround the front end part of the coated wire, and portions of the ends of the first and second crimping pieces at a front end of the barrel spaced from each other to define a communicating portion;

and

a molded portion surrounding the barrel over an entire periphery and entering the barrel through the communicating portion, the molded portion covering the front end part of the coated wire in a liquid-tight manner; wherein

the entire terminal fitting being accommodated in a terminal accommodation chamber formed in a housing.

4. The wire with terminal of claim 3, wherein:

the barrel is crimped to surround an exposed area of the core without contacting the insulation coating;

the molded portion covers the entire exposed area of the core including a crimped part to the barrel and a front end part of the insulation coating in a liquid-tight manner; and

the entire terminal fitting and only an area of the molded portion before the front end of the insulation coating are accommodated in the terminal accommodation chamber.

* * * * *
